UNITED STATES PATENT OFFICE.

DENNIS F. LARKIN, OF SAN FRANCISCO, CALIFORNIA.

PERAMBULATOR.

Application filed May 5, 1925. Serial No. 28,092.

This invention relates to improvements in perambulators and more particularly to safety tenders for small infants. Among the objects of this invention are to provide means for the healthful protection and amusement of infants between the ages of birth and walking; to give them the advantages of freedom of movement about the premises, while securely protecting them from cold drafts near the floor level; to provide the necessary muscular development in the arms and upper body, while the powers of locomotion are latent; to protect them from the dust and dirt, incidental to moving about the floor, while giving all the advantages of crawling without its incidental inconveniences to child and parent. When the child has arrived at the period of walking the perambulator can be converted into a trailing wagon.

Another object is to so ingeniously and scientifically design and proportion the body, that an infant placed therein cannot climb out or fall out, yet have full freedom of movement while in a sitting position.

A further object is to eliminate angles, corners and projections liable to injure the child and give to the structure sanitary features that will permit it to be thoroughly washed and kept sweet and clean.

It is a fact that an active infant will stand and walk before his anatomical development is capable of properly sustaining his weight, resulting in bow legs, broken arches, and unsymmetrical bodily development, especially in the nether limbs. The use of this invention, during this early period of infancy, develops initiative and mental activity, by giving free reign to the hands and arms, while protecting the lower limbs during that period that the bone structure is soft.

Other advantages and objects will appear as this description progresses. In this specification and the annexed drawings, the invention is illustrated in the form considered at this time to be the best; but it is to be understood that the invention is not limited to such form, because it may be embodied in other forms and it is to be understood that in and by the claims following the description it is desired to cover the invention in whatsoever form it may be embodied.

In the accompanying one sheet of drawings: Figure 1, is a side elevation of a baby tender constructed in accordance with this invention. Figure 2, is a plan view from

above of the same, partly broken away, to disclose the construction and mounting of the wheels.

In detail the construction illustrated in the drawings, comprises the underbody portion 1, having the fender 2, flanged outwardly therefrom. This underbody is panlike in formation, having a semicircular rear portion 3, rounded and flanged upwardly to provide a comfortable seat for the posterior of the occupant; with a forward extension 4, tapering gradually inward, with a sweeping curve where it terminates in the vertical front 5, to form a correct anatomical rest for the lower limbs, tending to hold them straight, with the feet pointing upward. The side walls 6, are perforated at intervals 7, to provide ventilation.

The fender 2 is preferably formed integrally with the underbody, and extends outwardly in sweeping curves across the front and along the sides of the body. Its outer edge is provided with a strip of felt or rubber 9, for the protection of the furniture into which the tender may be driven.

The parallel rear wheels 10, are mounted upon axles 11-11, secured in the hollow trunnions 12-12, secured in the plates 13-13 fixed to the sides of the underbody, by spot welding or otherwise. These wheels are set well to the rear to minimize the tendency to tip backward.

The front of the underbody is supported upon the caster wheels 14, the vertical stems 15, of which pivot in the brackets 16, which are fixed to and extend outward from the underbody, well forward. These pivots extend upward through the fender 2, to receive the ornamental "acorn" nuts 16, screwed thereon. To reduce production costs these nuts can be dispensed with by riveting the pivots 15, above the brackets 16 and not extending them through the fender. All wheels are provided with the rubber tires 17 and 18 respectively.

The upper body is flanged to fit snugly into the upper edge of the underbody at 19, and is detachably secured thereto at intervals by the screws 20. Or it may be permanently attached by spot welding or otherwise. This upperbody rises in streamlines from the lowerbody. The success of the invention, in preventing the infant occupant from falling or climbing out, depends upon the peculiar form of the upperbody.

The cockpit, formed by the opening in the

upperbody surrounded by the rolled edge 21, is set slightly forward of the rear wall of the underbody, to give the overhanging wall 22. If the infant grasps the rolled edge 21, 5 at the sides and attempts to lift himself up, his buttocks impinge against this overhanging wall 22, and prevent further lifting. In addition to the overhanging wall 22, the front deck 23, is of such a height that he is 10 unable to bend his knees and cannot, therefore, withdraw his body from the tender. Should he lean over sideways, his hips encounter the overhanging rolled edge 21, at the sides; which, in connection with the 15 straight knees, prevents dislodgment of his body. This invention has all the advantages to parent and child of the Indian papoose sling, plus anatomical freedom, locomotion and the promotion of infant initiative.

20 The holes 24, and 25, are provided in the upper body to receive the bent ends of the bail handle 26, preferably made of twisted wire, and convenient for older children or parents in pushing or pulling the tender in 25 transporting the infant.

Seated in the cockpit, the infant's hands naturally hang in contact with the rear wheels 10. Infants use their hands from birth, so they automatically grasp the rear 30 wheels and in a surprisingly short time, are propelling themselves about, to the delight of all concerned. They will sleep contentedly for hours leaning comfortably forward in the cockpit.

35 For additional comfort and to further prevent the bending of the knees, in attempt-

ing to climb out the bottom is anatomically shaped for the posterior, with the riser or "horn" 27, embossed in the bottom of the underbody portion 1.

40 The body portion is equally effective without the wheels and has its uses as such, in restraining without binding the child.

Having thus described this invention what I claim and desire to secure by Letters Patent is:

1. A baby tender comprising an elongated enclosed body with a substantially circular top opening of less diameter than the internal width of said body; rear wheels 50 mounted above the bottom of said body within reach of the occupant of the said body; and a rolling support for the front of said body.

2. A baby tender comprising an enclosed body with a semicircular rear portion; a tapering front portion and having a top opening of less diameter than said semicircular rear portion; rear wheels mounted above the bottom of said rear portion; a fender extending around said tapering front portion and a rolling support beneath said fender.

3. A baby tender comprising an elongated enclosed body with a substantially circular top opening of less diameter than the width 65 of said body; front and rear wheels whose axes are above the bottom of said body, and a handle with a bail having pivots adapted to engage holes in said body.

60 In testimony whereof I have hereunto af- 70 fixed my signature.

DENNIS F. LARKIN.
